UNITED STATES PATENT OFFICE

149,488

DESIGN FOR A COLLAPSIBLE DISPLAY AND SERVING STAND

Rose Halpern, New York, N. Y.

Application March 27, 1947, Serial No. 137,940

Term of patent 7 years

(Cl. D80—9)

To all whom it may concern:

Be it known that I, Rose Halpern, a citizen of the United States of America, residing in New York city, county of Bronx, and State of New York, have invented a new, original, and ornamental Design for a Collapsible Display and Serving Stand, of which the following is a specification, reference being had to the accompanying drawing, forming part thereof, wherein,

The front, rear and side members of the collapsible display and serving stand are identical in appearance.

I claim:

The ornamental design for a collapsible display and serving stand, substantially as shown and described.

ROSE HALPERN.
